CLAIM

The ornamental design for a baby carrier, as shown and described.

DESCRIPTION

FIG. 1 is a top, front perspective view of a baby carrier being worn in a first orientation, according to a new design;

FIG. 2 is a front elevational view of the baby carrier when not being worn;

FIG. 3 is a rear elevational view thereof;

FIG. 4 is a top, rear perspective view of the baby carrier being worn in the first orientation;

FIG. 5 is a side perspective view of the baby carrier being worn in a second orientation; and,

FIG. 6 is a front view of the baby carrier being worn in the second orientation.

The broken lines shown in the drawings depict portions of the baby carrier that form no part of the claimed design.

The broken lines shown in the drawing in FIG. 1 depicting portions of a person wearing the baby carrier are for purposes of illustrating use and environment only and form no part of the claimed design.
